CHARLES S. MACKENZIE, OF BOUND BROOK, NEW JERSEY

MEANS FOR SUPPORTING TROUSERS

Original application filed May 17, 1928, Serial No. 278,425. Divided and this application filed March 12, 1930. Serial No. 435,049.

The invention is an improved means of supporting trousers on the wearer without the use of suspenders or a belt worn around the outside of the waistband to the end that they will hang correctly and gracefully on the wearer and thereby present a neat and well-dressed appearance at all times and with comfort to the wearer.

Before proceeding with a description of my invention either generally or in detail, and in order to facilitate the description thereof, I desire it understood that whenever used herein the word "belt" will be intended to include all suitable kinds of girdles as well as all suitable kinds of belts. That whenever used herein the word "waistband" will be intended to include all and every part of the waist portion of trousers but more particularly the upper marginal part thereof; that whenever used herein the words "encircling belt" will be intended to include all suitable kinds of belts or girdles which are worn around the outside of the waistband for the purpose of supporting trousers; that whenever used herein the word "suspenders" will be intended to include all and every kind of braces and other trousers supporting devices that are held in place by means of straps or elastic bands, passing over the shoulders; that the description of the location of the trousers supports included in this invention, with reference to the wearer's feet contemplates the position of the feet when the wearer is standing in a normal position with his feet straight under him.

It is agreed by tailors and clothiers generally and is a matter of common knowledge among wearers of belts, that trousers cannot be made to hang to the best advantage by the use of encircling belts nor can trousers so supported maintain the position at which they are adjusted. On this account suspenders are commonly recommended or employed whenever graceful hang and appearance are greatly desired as in dress or evening clothes.

The reason why suspenders give a more graceful hang to trousers than do belts, is because they exert their supporting pull primarily at the front and rear parts of the waistband. This pull is usually exerted by

two arms on the front end of each strap that passes over the shoulders, which arms are buttoned to the waistband in positions which more or less straddle the vertical planes of the front creases customarily pressed in the front part of trousers legs. The rear part of the suspenders, whether fastened to the waistband by two or more arms, impart an upward pull to the rear part of the trousers on both sides of the spine although that pull is likewise inward toward the spine. It is by reason of the upward pull being exerted primarily at the points indicated that suspenders permit or cause the trousers to hang free with considerable grace around the body and legs of the wearer. But I have discovered that a perpendicular pull exerted in the waistband in perpendicular alignment with the front and rear creases customarily pressed in trousers legs imparts a still more graceful hang to the trousers. In the case where trousers are sustained by an ordinary belt the waistband is compressed more or less equally around the entire body and the supporting pull is thus exercised at all points of the waistband regardless of the number of belt loops employed; the effect of which is to cause the trousers to drag and bind against the wearer's legs and form in transverse folds and wrinkles when he walks, and generally to detract from the appearance which good pressing and creases are intended to impart. Furthermore it is common knowledge among users of belts that they slip downward during the process of sitting, stooping or otherwise flexing the body, and thus cause the trousers to assume a slovenly and ungraceful appearance.

But a large percentage of men in this country prefer to use belts rather than suspenders, as trousers supports, notwithstanding their admitted inefficiency and drawbacks, as they find them more comfortable and convenient than suspenders and because they present a much neater appearance when coat and vest are removed.

The general object of the invention is to afford a method and supply means of supporting trousers possessing all of the advantages of both suspenders and belts as well as other

advantages without the disadvantages of either. More specifically stated, the object of the invention is to provide a method and means by which trousers can be suspended from, or held in position at the waist of the wearer, in such a manner that there will be as little contact as possible between the trousers legs and the wearer's legs; that they will be as free as possible from transverse and angular folds and wrinkles; that they will not sag or slip down around the waist and legs when the wearer sits down, stoops, or otherwise flexes the body; that they can be easily raised or lowered without unbuttoning the vest or trousers; that they will hang in straighter and more graceful lines than it would be possible for them to do if they were suspended on the body by means of any kind of an encircling belt or even by the usual type of suspenders; also to produce a device neat in appearance, highly practical, moderate in price, and so designed and constructed as to enable the wearer to easily and quickly attach the trousers thereto or disengage them therefrom and which will afford greater comfort to the wearer and materially improve the appearance of his trousers and which will also overcome the inconvenience, discomfort and annoyance, occasioned by wearing suspenders, encircling belts and any known kind of interior belt or trousers support.

My invention accomplishes these results through the use of suitable attachment elements or hooks to be affixed in the inner side of the waistband at said four points and suitable movable supporting elements to be carried on said belt in the same perpendicular plane as the attachment elements, together constituting the subject of this invention, and all of which is more specifically described hereafter and exemplified in the accompanying drawings. This application is a division of my copending application Serial Number 278,425 filed May 17, 1928.

Figs. 1 and 2 illustrate more or less diagrammatically the necessary relation of the points of support to the feet of the wearer;

Fig. 3 is a perspective view of a portion of the belt with the preferred form of supporting element supplied;

Fig. 4 is a horizontal section through the belt supporting element, attachment element and waistband in position or slightly separated for clearness;

Fig. 5 is a vertical section of the same;

Fig. 6 is the attachment element or hook designed to cooperate with the supporting element of Fig. 3.

The belt 1 may be any ordinary belt with a suitable adjustment means or buckle 2. It is worn over the shirt, not shown, or other undergarment, so that it is inside of the waistband.

The letters A, B, C, and D mark the four points at which the trousers are supported

according to this invention and as indicated by the dotted line, they will be seen to be located respectively vertically above the center of the instep, or forward part of the foot, and the center of the heel, or back part of the foot. The location of said four points of support is most important and requires to be stated since even a moderate variation will throw the trousers out of balance with the axis of the leg and thereby will result in the objections referred to. Although the diagram of the drawing shows the points A, B, C and D in parallel planes, it will be understood that this is for clearness of illustration and that their position is in any event in the vertical planes of the axes of the two feet of the wearer when they are parallel and facing straight forward.

As a preferred form of supporting and attachment means, I employ an element comprising a metal plate with off-set end portions 3 vertically slotted to receive the belt, and a central portion provided with a vertical series of identical horizontal crossbars 4 equally spaced from one another, like a ladder. This central portion is disposed on the outside of the belt and by the arrangement of the offsets is spaced slightly away from it to provide clearance for the head 5 of the attachment element, shown in Fig. 6. The vertical slots in the off-set end portions 3 are of a width slightly wider than the thickness of the belt sufficient to allow the supporting element to be readily worked along the belt either forward or backward as desired, when the belt is loose, by exercising a moderate degree of force with the fingers, but not sufficiently wide to permit the supporting element to slide along it without pressure. The purpose of this is to prevent a change of position of the supporting element, due to slipping along the belt, when the belt is removed from the body.

The horizontal slots between the crossbars 4 are designed as to vertical width with reference to the length of the head 5 of the attachment element shown in Fig. 6 as well as with reference to the thickness of the crossbars 4 and their distance from the underlying portion of the belt, so that the T-shaped head of the attachment element can be inserted in any of said slots as desired at an angle so that the guard part at the top of the head 5 will just clear the nearest upper crossbar 4 of the supporting element and rest under it as the arm supporting the head 5 comes in contact with and rests on the next lower crossbar. It is obvious that if the head of the attachment element were too long with reference to the vertical width of the horizontal slots, the thickness of the crossbars, and the distance they are away from the underlying portion of the belt, all of the head and particularly the guard part at the top thereof could not enter such slots, as the head having to

enter the slots at an angle would come in contact with the underlying belt and its progress be stopped. Conversely if the slots had too great vertical width, with reference to the 5 length of the head 5, the thickness of the crossbars 4, and the distance the underlying portion of the belt is away from the crossbars, the angle at which the head 5 could enter or be removed from the slots would be so slight that there would be grave danger of 10 the attachment element becoming accidentally disengaged from the supporting element shown in Fig. 3.

In order to facilitate the insertion of the 15 head 5 of the attachment element Fig. 6 in the slots between the crossbars 4 the head portion 5 is set at an angle to or slightly curved away from the base 7. The head 5 is offset from the base 7 of the attachment element Fig. 6 a sufficient distance so that the lower part of the base 7 will not come in contact with any of the crossbars 4 when the head of the attachment element is being set 20 in any of the slots between the cross bars 4.

25 By constructing the engaging part or head part of the attachment element as above indicated, with reference to the central portion of the supporting element as above described, the attachment element can easily and quickly be engaged with the supporting element by pushing the hook part 5 of the attachment element inward and downward through the desired slot in an arc-like direction, and may, as easily and quickly, be disengaged therefrom, by pulling the attachment member upward and outward in an arc-like direction. The fact that it is almost impossible to disengage the attachment element from the supporting element except by an arc-like motion 30 upwards and outwards prevents it from becoming accidentally disengaged.

35 This attachment element is secured in any appropriate manner to the inner face of the waistband 6 and its T-shaped head is adapted, as above described, to be introduced between any of the crossbars 4 by first inserting the lower hook end or point of the head and then pushing it inward and downward in an arc-like direction, so that the guard 40 part comes under the next upper crossbar and the base of the attachment element becomes parallel with the belt surface. In this position, Fig. 5, accidental disengagement is safely prevented. The attachment element 45 may be secured to the waistband by sewing, for which purpose its base 7 is perforated as indicated, or it may be secured in any other appropriate way, but in any case an attachment element is carefully located at each of the four points of support as hereinbefore indicated. The supporting elements are first located on the belt as nearly as may be, to be in alignment with the attachment elements, when the trousers are being worn, and 50 the belt is then fastened around the wearer's

waist at the desired tension; the trousers are then buttoned up and the four points in the belt in the vertical planes of the front and rear attachment elements respectively on the waistband are noted; the belt is then loosened and the supporting elements are moved along it as required so that they will be in position to register with the hooks of the attachment elements and the belt is again fastened to the desired tension; the attachment 55 elements are then engaged with the particular crossbars of the supporting elements both in the front and in the rear as will conform to the height to which the trousers have been pulled at said four points respectively. Any 60 slight lateral variation of the position of the supporting elements with reference to the attachment elements is of no importance provided it is slight for the reason that the horizontal slots of the supporting elements are 65 purposely made about one half inch longer than the width of the head of the attachment element, so as to compensate for any such variation and in order to permit self-location 70 of the attachment elements in their respective 75 predetermined and correct positions.

It is advisable to affix the attachment elements to the lower margin of the waistband at the four points of support, as this will usually permit of about one inch increase in 80 vertical adjustment of the trousers. It also provides a maximum of waistband to cover 85 the belt so in most cases to entirely conceal it.

It will be apparent that within the principles above explained the invention can be 90 embodied in numerous forms and applied in a variety of ways.

Having described my invention, I claim:

1. A trousers-supporting device comprising a supporting element adapted to be carried on a belt worn underneath the trousers having its two terminal portions offset and slotted to receive the belt and be supported by it, and having its central portion spaced from the outer side of the belt and consisting of a vertical series of horizontal crossbars 100 equally spaced from one another forming intervening slots and an attachment element on the inner side of the waistband of trousers having a head adapted to enter any of said 105 slots.

2. A trousers-supporting element composed of rigid material to be carried on a belt to be worn underneath the trousers having its side terminal portions vertically slotted to receive the belt and be supported by it and having its central portion spaced from the outer side of the belt and consisting of a vertical series of crossbars spaced from one another, in combination with an attachment 110 element consisting of a flat base suitably designed and constructed to enable it to be fastened to the inner portion of the waistband of trousers and an arm which is offset 115 from the base which carries on its end a head 120

consisting of a hook part and a guard part the hook part of which is under said arm and the guard part of which is above said arm, which said head is set away from the base 5 and is designed and constructed to be inserted in one of the slots between any two of said crossbars, the arm part thereof supporting the trousers by resting on the underlying crossbar over which the hook part has 10 been passed and the guard part thereof preventing accidental disengagement by coming in contact with the next overlying crossbar when any upward pressure is exerted 15 other than a combined outward and upper pressure.

3. A trousers-supporting element composed of rigid material to be carried on a belt to be worn underneath the trousers having its side terminal portions vertically slotted to receive the belt and be supported by it, said vertical slots having a lateral width to easily accommodate the thickness of the belt and allow the supporting element to be worked along the belt either forward or backward 25 as desired when the belt is loose on the body by exerting a moderate degree of force with the fingers but preventing unintentional displacement when the belt is removed from the body, and having the length 30 of said slots slightly greater than the width of the belt; said supporting element also having in its central portion a vertical series of crossbars equally spaced one from another and spaced from the outside of the belt and 35 having the thickness of said crossbars, the width of the spaces between them and the distance of the crossbars from the underlying belt all designed with reference to the attachment element to be used in conjunction 40 with said supporting element so that the head of the attachment element may be inserted between any two of said crossbars at an angle and the top or forward part thereof will just clear and rest under the overlying crossbar 45 when the arm supporting the head of the attachment element rests on the underlying crossbar.

4. A trousers-attachment element composed of rigid material consisting of a flat 50 base suitably designed and constructed to enable it to be fastened to the inner portion of the waistband of trousers, an arm which is offset from the base and carries on its end a head consisting of a hook part which is under 55 said arm and a guard part which is above said arm and said head being set at an angle away from said base, in combination with a supporting element carried on a belt worn around the waist inside the trousers waistband the engaging part of which supporting element consists of a vertical series of horizontal crossbars equally spaced from one another and offset from the underlying and supporting belt, the length of the head part 60 of said attachment element and the angle 65

which the hook part thereof bears to its base being determined with relation to the thickness of the crossbars, the width of the intervening slots and the distance of the crossbars from the underlying belt, so that the head 70 part may easily be inserted between any two of said crossbars and so that when so inserted the offset arm will rest on the underlying crossbar, and the guard part end of the head will be underneath and almost contiguous with the next overlying crossbar thus precluding disengagement therefrom except by means of an outward and upward or arc-like motion.

5. A trousers-supporting device to be carried on a belt worn underneath the waist portion of the trousers, comprising a plate provided with a vertically extending opening to receive the belt and being adjustable longitudinally thereon, said plate having a plurality of horizontal attachment-receiving bars exposed on the outer face of the belt and forming a plurality of intervening slots between them, in combination with an attachment element adapted to be affixed to the inner face of said waist portion of the trousers and formed to enter in any of said slots, said element being of less horizontal dimension than said slots whereby it may assume any predetermined position with reference 95 to said plate.

In testimony whereof, I have signed this specification.
